METAL WINDOW CONSTRUCTION

David T. Bjork, Evanston, Ill.

Application April 7, 1948, Serial No. 19,545

9 Claims. (Cl. 189—66)

1

This invention relates to window constructions, and particularly to improvements in sliding sash windows having pivot means whereby the windows may be swung pivotally in the window frame to permit easy access to the outside face of the window glass.

The main objects of this invention are to provide an improved sliding sash window construction; to provide a window construction having improved operating means for a pivoting sliding sash; to provide an improved window sash having retractable guide rails to free the sash from the frame in which it slides; to provide an improved pivot bolt arrangement for pivoting-sliding sash windows; and to provide an improved arrangement for simultaneous operation of retractable guide rails and extensible pivot bolts in sliding sash windows.

Further objects are to provide an improved sash construction for pivoting-sliding sash windows; to provide an improved construction for mounting pivoted-sliding sash windows; to provide an improved construction of retractable sash guide rails and pivot means whereby the window sash is at all times positively retained in the sash frame; to provide such a construction that is adaptable to either metal or wooden sash construction; and to provide an improved retractable guide rail and pivot means that may be readily applied to existing sliding sash windows.

Still further objects are to provide an improved arrangement for hanging pivoting sliding sash windows; and to provide such a construction in which the window sashes may be safely supported when swung on their pivots so as to obviate the possibility of the window being dropped during the pivoting operation.

A specific embodiment of this invention is shown in the accompanying drawings in which:

Figure 1 is an inside face view showing the general appearance of the improved pivot-slide window construction.

Fig. 2 is a sectional elevation of the same, showing the pivoted positions of the window sashes in dotted outline.

Fig. 3 is a fragmentary sectional view, taken on line 3—3 of Fig. 1, showing the arrangement of the window frame head.

Fig. 4 is a sectional view as taken on line 4—4 of Fig. 1, showing the sash arrangement and the construction of the window frame jamb.

Fig. 6 is a sectional view as taken on line 5—5 of Fig. 1, showing an arrangement of the upper and lower window sashes at the parting rails.

Fig. 6 is a fragmentary sectional detail show-

ing a modified arrangement for sealing the window sash parting rails.

Fig. 7 is a sectional view as taken on line 7—7 of Fig. 1, showing the construction and arrangement of the bottom window sash rail and the window frame sill member.

Fig. 8 is a fragmentary perspective view of the lower and right-hand portion of the window sash, partly broken away to show the pivot bolt and retractable guide rail operating mechanism.

Fig. 9 is a fragmentary perspective detail view showing the arrangement of the retractable guide rail operating element for the window sash.

Fig. 10 is an inside face view of the operating handle, showing its construction and operating arrangement.

Fig. 11 is a sectional view of the same as taken on line 11—11 of Fig. 10.

Fig. 12 is a fragmentary face view of the window sash in elevation illustrating the operation of the retractable sash guide means and the pivot, the several operative positions of the sash guide means and pivot being shown in dotted outline.

Fig. 13 is a sectional plan view through the window frame head illustrating an arrangement of spring actuated sash balancers for supporting the sliding window sashes; and

Fig. 14 is a fragmentary sectional view as taken on line 14—14 of Fig. 13 showing the sash cord locking arrangement for permitting the sashes to be held in pivoted or inwardly swung position.

In the form shown in the drawings, the invention is embodied in a double-hung window sash arrangement wherein a metal window frame and sash construction is employed. In this arrangement independent upper and lower windows 1 and 2 respectively are mounted, one above the other, in a frame 3 and disposed so as to be slideable vertically in parallel spaced planes in the same manner as the ordinary double-hung sliding sash windows. The window frame 3, however, being made of metal, is of the hollow box type of construction; and the window sashes 4 are made of metal elements having a uniform cross section throughout and arranged to fit into appropriate portions of the frame side members and be slideable therewith in a vertical direction.

Since the window sashes are to be mounted so that they can be pivoted in the window frame, the upper and lower sashes must be of different over-all widths, whereby the outermost window can pass the vertical stop for the inner window. In the construction shown, the upper window 1 is made of lesser width than the lower window 2, since it is preferable that the upper sash be outer-

most in order to have an adequate seal at the parting rails between the upper and lower sashes.

This arrangement of the sashes as well as the construction of the side members, or jambs, of the window frame is illustrated in Fig. 4, and, as shown, the jamb 5 is of hollow form constructed to fit into the window opening 6 of a building wall and is made with its face formed to provide three progressive steps, each lying in a different plane, with the highest step, relative to the window opening, being outermost. The two shoulders 7 and 8 thus formed between the steps, provide the stops for the respective sashes of the windows 1 and 2 and the windows are mounted to slide on the respective steps between opposed jambs; it being understood that the opposite jamb and sash arrangement is the same as that shown in Fig. 4.

Each window sash is of the same construction, the only difference being in the relative widths, and in the form shown, the sash is made from metal top, side and bottom members suitably joined to form a rectangular frame. These frame members are all of the same shape and section, to facilitate manufacture and assembly of the sashes, and referring to Fig. 4, it will be seen that the section is generally of S form to provide two oppositely opening channels 9 and 10.

The inwardly opening channel 9 is defined by middle leg or partition 11, between the channels, and by a short outer leg 12 which is preferably about one-half the height of the partition 11. The outwardly opening channel 10 is defined by the partition 11 and an outer leg 13 which is of substantially the same height as the partition. The outer channel 10, however, is much narrower than the channel 9, being only about one-third the width of the latter, while the channel 9 has a width substantially equal to the height of the leg 12.

As shown, the jamb 5 is formed to provide channels or grooves 14 and 15 positioned to align with the channels 10, of the respective sashes, when the sashes are in engagement with the respective stops 7 and 8, also each sash is provided with a tongue or guide rail 16 disposed in the channel 10 and projecting outwardly therefrom into the respective jamb groove. These tongues or guide rails are attached to the respective sashes and serve as means to hold the sashes in place in the window frame as well as runners on which the sashes slide up and down in the frame. The guide rails 16 are, however, only provided on the side members of the sash frames, as will hereafter appear, since their purpose is to engage the jambs and hold the windows in their normal slideable position between the jambs.

The tongues or guide rails 16 are slidably mounted in the respective channels 10, so as to be retractable thereinto by means of suitable operating means to be hereafter described and, in the form shown, are U-shaped members formed of sheet metal and arranged to closely fit the sash channels 10 and the respective jamb grooves 14 and 15, so as to serve as weather strips as well as guide members. The legs of the U-shaped tongues extend into the channel 10 and bear resiliently against the sides thereof. These tongues extend substantially the height of the sash frame, being only slightly shorter for operational purposes, and are of a width equal substantially to the depth of the channel 10 in order that they may be fully retracted to disengage the sash from the jamb. This arrangement and operation of the tongues 16 is shown in Fig. 12.

The construction of the frame head member and the arrangement of the upper sash frame

top member is shown in Fig. 3, and it will be seen that the head member 17, like the jamb 5, is a hollow box-like form arranged to fit and extend along the top of the window opening. The back side of the head member is, however, closed by means of a plate 18, suitably secured, in order to provide an enclosure for sash balancer mechanisms which will be later described.

The front side of the head member 17 is generally level and flat since it normally provides engagement only for the top member of the upper sash. However, one step 19 is formed in the front surface to provide a shoulder 20 to serve as a top horizontal stop for the upper sash. The step 19 and shoulder 20 are formed to correspond with the outer step and the shoulder 8 of the jambs and it will be understood that these portions of both the head member and the jambs are aligned in the assembled frame construction.

As shown in Fig. 3, the top member of the upper sash frame, indicated generally by 21, is of a construction identical with that of the side members of the sash frame shown in Fig. 4 and the outer leg 13 of the top member fits against the shoulder 20 when the sash is in closed position. The channel 10 of the top sash member serves in this case to retain a suitable sealing member 22 adapted to protrude from the channel to engage the front face of the head member 17. The sealing member may or may not fill the channel 10 of the top member 21 as desired. As shown the sealing member 22 is a rubber strip set into the channel 10 and arranged to provide a weather seal between the head member 17 and the upper window sash when the sash is in closed position.

The relation of the parting rails of the upper and lower sashes and an arrangement for sealing the space between them is shown in Fig. 5. These parting rails comprise the bottom member of the upper sash frame and the top member of the lower sash frame and these members are of the same size and shape as the side members of the sash frame, as before mentioned. However, since the sashes are disposed in different planes and some space is necessary between them, a suitable seal must be provided when the sashes are in closed position. One form of such a seal is shown in Fig. 5, and comprises a resilient clip 23 mounted on the bottom member of the upper sash frame and having an upwardly rolled edge 24 adapted to engage and resiliently bear against the upper member of the bottom sash frame. The clip 23 is a strip-like element which extends the length of the bottom member of the upper sash frame and is provided with a leg 25 which lies against the outer surface of the leg 12 of the said bottom member and is secured thereto by means of a clamping bar 26 held in place by suitable screws 27 which are threaded into tapped openings in the leg 12. The clip 23 may be made of any suitable resilient material, such as Phosphor bronze.

A modified arrangement for sealing the space between the sash parting rails is shown in Fig. 6 and in this case the sealing member comprises a rubber strip 28 seated in a channel strip 29 riveted, or otherwise secured on the leg 12 of the bottom member of the upper sash frame. Both the strip 28 and its mounting channel 29 extend the entire length of said bottom member and the width of the strip 28 is such that, when the sashes are in closed position, it will tightly engage the leg 13 of the upper member of the lower sash frame.

The construction of the window frame sill and

the relation of the bottom member of the lower sash frame thereto is shown in Fig. 7. The sill 30, like the other window frame members, is also a hollow box construction of metal and is formed with stepped sash engaging surface. The inner step 31, however, is the highest and extends from the inside edge of the sill outwardly to a point substantially aligned with the channel 10 of the bottom member of the lower sash frame where the sill surface drops to form a shoulder 32 and then runs outwardly in a downward incline to the outer edge of the sill.

This arrangement is to provide a sealing corner, on the sill, for the lower sash frame and to afford outward drainage of rain or other water that might fall upon the sill. In this case the weather seal between the lower sash and the sill 30 is provided by means of a gasket 33 of yieldable material, such as rubber, which is disposed in the channel 10 of the bottom member of the sash frame and arranged to project slightly therefrom to form a lip 34 which will yieldably engage the corner formed by the shoulder 32 and slightly overhang the same. Thus when the lower sash is in closed position against the sill 30 a secure weatherproof joint is provided.

As indicated in Figs. 5 and 7 and as shown in Figs. 8 and 12, each of the sashes is provided with a pivot bolt 35 disposed in the bottom member of the sash frame, there being one such pivot bolt on each side of each sash. These pivot bolts are arranged to be projected laterally from the sides of the sashes and into suitably located openings in the window frame jambs, to provide pivot means for swinging the sashes inwardly when the sash tongues or guide rails 16 are retracted from the jamb grooves.

Preferably the pivot bolt 35 and the tongues 16 on both sides of each sash are operated simultaneously by a single operating means mounted on the bottom sash frame member. In this manner it is assured that either the tongues 16 or the pivot bolts 35 will be engaged with the jamb to prevent accidental dropping or falling out of the window sash when it is desired to swing the sash in order to easily reach the outer window pane surface.

The pivot bolt and retractible tongue construction is the same for each sash and the arrangement is the same on each side of the sash, excepting only that one side is right hand and the other left hand, as will be readily understood. As shown in Figs. 8 and 12, the pivot bolts 35 are disposed in the channel 9 of the bottom sash frame member and are arranged for operation by means of an operating handle or lever 36 located at the center of the bottom sash frame member. These pivot bolts are arranged to slide laterally in the channel 9 and to be projected outwardly through suitably aligned openings 37 in the sash side members, from which they enter suitable openings, not shown, in the window frame jamb 5.

In order to provide simultaneous operation of the tongues 16 and the pivot bolts 35, a connecting crank arm arrangement, mounted in the corner of the sash frame, is utilized. This crank arrangement comprises a shaft 38 disposed transversely of the channel 9, in which the pivot slides, and having its inner end journaled in the partition 11 of the sash side frame member and its outer end supported and journaled in the corner plate 39 mounted in the corner of the sash frame against the short inner legs 12. This

corner plate has a rectangular boss 40 which fits into the corner where the edges of the legs 12 meet and the journal is in this boss so that the axis of the shaft 38 is outside of the relatively short legs 12 and intersects the partition 11 near the bottom of the groove 10 in which the tongue 16 slides.

As shown, a crank arm 41 is mounted fast on the inner end of the shaft 38 and is disposed centrally in the channel 10 of the sash frame side member where it extends between the legs of the tongue 16 and is pivotally connected, at its free end, to the tongue as at 42. Within the channel 9 of the bottom sash frame member and above the pivot 35, the crank shaft 38 is provided with a second crank arm 43 extending from a hub 44, secured on the crank shaft by means of a lock screw 45, into an opening 46 formed in the pivot 35.

This arrangement is shown in detail in Fig. 9 and it will be seen that as the pivot is moved laterally the motion will be imparted to the arm 43, so as to rotate the shaft 38, thereby swinging the arm 41 connected to the tongue 16 and causing the tongue to shift in and out of its retaining groove 10 in the sash frame side member.

The several positions of the pivot 35 and the tongue 16 are illustrated in Fig. 12 where the full outline shows the tongue 16 in its operative or extended position when the bolt or pivot 35 is fully retracted. The dotted outline A, of the tongue 16, shows its fully retracted position at which position the pivot 35 is fully projected as at A¹. The intermediate positions of the tongue and pivot are indicated by the dotted outlines B and B₁, respectively, and in those positions both the tongue and the pivot are partially projected from the sash and engaged with the jamb. This is the locking position of the elements wherein the sash is not only keyed to the jamb but is also locked against vertical sliding movement, as when it is desired to lock the sashes in partly opened or fully closed positions.

As shown in Fig. 12, the upper end of the tongue 16 is supported on a fixed pin 47, which extends across the channel 10 through an arcuate slot 48 formed in the legs of the tongue. The pin 47 thus serves to retain the upper end of the tongue in its channel and to guide the tongue as it moves in and out of the channel under the influence of the arm 41.

Details of the operating lever arrangement are shown in Figs. 10 and 11, and it will be seen that the lever 36 is pivotally mounted on the inner leg 12 of the bottom frame member of the sash by means of a pivot 49 extending through the leg 12 and secured by a threaded connection with a suitably tapped opening in the leg 12. The lever 36 is backed by a shield plate 50 which serves the dual function of holding the lever firmly against the leg 12 and of hiding the lever position from view from the outside of the window. The shield plate 50 is secured by means of bolts 51 which extend through the leg 12 from the inner side thereof.

The operative connection between the lever 36 and the pivot bolts 35 is had by means of a pinion 52 which extends between the leg 12 and the shield 50 and is rotatably supported on a bolt 53 which extends through the leg 12 and is threaded into the shield. The pinion 52 is driven by means of an arcuate rack 54, formed on the upper margin of an opening 55 provided in the lower end of the lever 36 and through which the pinion extends, and the pinion, in turn, drives a pair

of rack bars 56 and 57 which are connected to the respective pivot bolts 35 by means of pins 58. The rack bars are positioned above and below the pinion, in vertical alignment, so as to operate in opposite directions upon rotation of the pinion and guided by slots 59 and 60 formed in the base portion of the shield 50. Thus, by operation of the lever 36 from one side to the other, the pivot bolts 35 are caused to be projected from the sides of the sash frame or retracted into the sash frame as the case may be. At the extreme positions of the lever 36, the pivot bolts are either fully extended or fully retracted; and at the mid position of the lever the pivot bolts are in their partially extended locking position.

It will be understood that a lifting handle 61 may also be mounted on the bottom frame member of the lower sash, as indicated in Fig. 1, to facilitate raising and lowering the sash.

As before mentioned, it is preferred that the sashes be hung or supported from spring sash balancers housed in the window frame head member and such an arrangement is shown in Fig. 13, wherein spring balancers 62 and 63 are provided for the respective sashes. Each spring balancer is mounted in the frame head 17 on a vertical axis and the respective sash cords 64 and 65 extend from the balancer to the ends of the head where they pass downwardly, over suitable pulleys 66, to the upper ends of the respective sashes where the cords are attached in notches formed in the sash frame. This arrangement of sash balancing means is well known in this art and will be readily understood.

The pulleys 66, however, are specially designed to provide a position locking or clamping means for the sash cords so that when the sashes are swung open on their pivots the tension on the sash cord due to the balancers will be relieved. Such a sash cord clamping arrangement is shown in Fig. 14 wherein the pulley 66 is formed with a toothed or notched flange 67 and is horizontally journaled in a housing 68 having a side opening 69 through which the cord can swing laterally. The side opening extends upwardly from the bottom of the housing 68 to a point substantially at the level of the pulley axis and terminates in a curved end 70 which extends outwardly parallel with pulley flange 67.

Thus, when the sashes are swung inwardly to their pivoted position, shown in dotted outline in Fig. 2, the sash cords 64 and 65 are pulled inwardly so that they extend at an angle across the pulley flange 67, and when the downward pull on the cords is released the cord is clamped by the flange notches against the end 70 of the housing opening and held against the action of the respective balancer. Slotted openings 71, at the ends of the head member 17, through which the cords pass, permit such inward angular pull on the cords.

It will now be seen that, with this arrangement for the sash cords, the sashes may be set to an inwardly swung position for cleaning purposes and safely retained in that position until it is desired to close them. When returning the sashes to their normal position in the window frame it is only necessary to pull downwardly on the respective sash cords and then push them to a vertical position where they are free of the notched pulley margins and will run freely over the pulley under the influence of the sash balancer.

As shown in Figs. 3, 4, 5 and 7, the window panes are mounted in the sash frames by means of spring clips which set into the frame channels

9 and bear resiliently between the legs 12 and the window pane to press the same toward the partition 11 of the sash frame section. The glass panes are set into the sash frames from the inner side and it will be understood that at least one dimension of the pane must be slightly less than the corresponding distance between the end edges of the inner frame section legs 12. The glass panes then rest against the partition portions 11 of the sash frame and are sealed by means of an adhesive gasket 72, adapted to adhere to both the glass and the partition 11, which extends from end to end of the glass margin.

The mounting clips 73 are square U-shaped members made of a stiff resilient material, such as Phosphor bronze, and are disposed with their legs extending into the sash frame channels 9 and their closed sides spanning the space between the glass pane and the leg 12 of the sash frame. These mounting clips are formed to extend across the width of the frame opening and abut each other at the frame corners so as to completely close the opening between the leg 12 and the glass around the entire inner periphery of the frame.

Preferably the length of the mounting clip legs is such as to extend well into the channel 9 and at the same time provide ample bearing on the glass pane to hold it against the adhesive gasket 72 and, to secure the mounting clips in the desired position, laterally spaced pins 74 are provided to extend across the channel 9 through suitable openings in the mounting clip legs.

The normal operation of the improved pivot-slide window sash is the same as with ordinary sliding sash windows, the jamb stops 7 and 8 and the tongues or guide rails 16 serving to seal the sliding jamb connection and retain the sashes within the window frame. During such normal operation the pivot bolts 35 are fully retracted and the tongues 16 are fully extended. When it is desired to pivot the sashes, the operating lever 36 is swung to the left to retract the tongues and extend the pivot bolts and suitable openings, not shown, are provided at predetermined locations in the jambs to receive the bolts. Preferably the bolt openings for both sashes are located at the lower ends of the jambs, for convenience in reaching the outer glass surfaces, and the bolt openings for the outer or upper sash are located at a higher level than the bolt openings for the lower sash. Thus when the sashes are positioned to align the pivot bolts with their respective jamb openings and the bolts are extended by the operating lever 36, the tongues are simultaneously retracted, clear of the jamb grooves, and the sashes may be swung inwardly.

In order to permit locking of the sashes in partly opened position, when in normal sliding engagement with the jambs, additional pivot bolt openings are provided in the jambs to receive the pivots at predetermined levels of the respective sash frame bottom members. Thus when the sash is shifted to the desired one of the predetermined partly opened positions, the operating lever 36 is shifted to its mid position where the pivot bolt is partly projected and the tongue 16 is only partly retracted, and the sash is securely locked in the window frame against any movement whatsoever.

The main advantages of the improved pivot-slide sash arrangement reside in the simple construction of the sliding tongue and extensible pivot bolt mechanism whereby these devices are simultaneously operated to provide positive en-

gagement of the sash with the window frame jamb at all times; and in the arrangement of the mechanism so that it can be readily utilized in either new or existing sash constructions without altering their normal operation or seriously changing their mounting characteristics.

Other advantages are to be found in the improved sash construction which permits standardization of the sash frame members and results in lower manufacture and assembly costs; and in the improved and simplified window pane mounting means whereby the installation or replacement of the glass in the sash frames may be done more quickly and easily than with present methods.

Further advantages reside in the improved all metal construction of the window sashes and frames; and in the simplified jamb arrangement which provides a secure weather-tight mounting for the sashes and at the same time permits them to be readily pivoted and swung inwardly for access to the outer pane surfaces.

Although but one specific embodiment of this invention is herein shown and described, it will be understood that numerous details of the construction shown may be altered or omitted without departing from the spirit of this invention as defined by the following claims.

I claim:

1. A sliding sash window construction comprising a sash frame having opposite side frame members and a laterally projecting tongue element extending along each of said side frame members, said side frame members each having a longitudinal channel adapted to receive and house the respective tongue element, each of said tongue elements being mounted in its respective channel and adapted to be slidably retracted thereinto, an axially slidable pivot pin element adapted to be projected laterally from each of said side frame members, means in each side frame member for shifting one of said elements laterally relative to the respective frame member, and driving means connecting said one element with the other element in each side frame member and adapted to simultaneously shift said other element in the direction opposite the movement of said one element.

2. A sliding sash window construction comprising a sash frame having opposite side frame members and a laterally projecting tongue element extending along each of said side frame members, said side frame members each having a longitudinal channel adapted to receive and house the respective tongue element, each of said tongue elements being mounted in its respective channel and adapted to be slidably retracted thereinto, an axially slidable pivot pin element adapted to be projected laterally from each of said side frame members, driving means connecting the tongue and pivot pin elements of each side frame member and adapted to transmit motion from one element to the other in the opposite direction, and operating means extending between said side frame members and connected to one of the said elements of each side frame member for actuating both of the elements of both side frame members simultaneously.

3. A sliding sash window construction comprising a sash frame having opposite side frame members and a laterally projecting tongue element extending along each of said side frame members, said side frame members each having a longitudinal channel adapted to receive and house the respective tongue element, each of said

tongue elements being mounted in its respective channel and adapted to be slidably retracted thereinto, an axially slidable pivot pin element disposed adjacent the same end of each side frame member and adapted to be projected laterally beyond the outer margin thereof, means in each side frame member for shifting one of said elements laterally relative to the respective frame member, and driving means connecting said one element with the other element in each side frame member and adapted to simultaneously shift said other element in the direction opposite the movement of said one element.

4. A sliding sash window construction comprising a sash frame having opposite side frame members and a laterally projecting tongue element extending along each of said side frame members, said side frame members each having a longitudinal channel adapted to receive and house the respective tongue element, each of said tongue elements being mounted in its respective channel and adapted to be slidably retracted thereinto, an axially slidable pivot pin element disposed adjacent the same end of each side frame member and adapted to be projected laterally beyond the outer margin thereof, motion transfer means operatively connecting each tongue with its respective pivot pin for simultaneous shifting of one by the other and in opposite directions relative to each other, and operating means extending between said side frame members and adapted to actuate the pivot pins of both side members simultaneously.

5. A sliding sash window construction comprising a sash frame having end members and opposite side members and an outwardly opening channel extending along each of said opposite side members, a laterally shiftable tongue element disposed in and extending along each channel, each of said tongue elements being adapted to be projected from the respective channel and retracted into said channel, a laterally shiftable pivot pin element housed within each end of one of the end members of said sash frame, each of said pivot pin elements being adapted to be extended from and retracted into said end member, and motion transfer means housed within each of the respective frame members and operatively connecting each tongue element with the respective pivot pin element for simultaneous shifting movement of one element by the other and in the opposite direction relative to the other.

6. A sliding sash window construction comprising a sash frame having top and bottom end members and opposite side members and an outwardly opening channel extending along each of said opposite side members, a laterally shiftable tongue element disposed in and extending along each channel, each of said tongue elements being adapted to be projected from the respective channel and retracted into said channel, a laterally shiftable pivot pin element housed within each end of one of the end members of said sash frame, each of said pivot pin elements being adapted to be extended from and retracted into said end member, motion transfer means housed within each of the respective frame members and operatively connecting each tongue element with the respective pivot pin element for simultaneous shifting movement of one element by the other and in the opposite direction relative to the other, and common operating means mounted on said one frame end member and connected to one of the said elements of each of said side

members for actuating the tongue and pivot pin elements of both side members simultaneously.

7. A sliding sash window construction comprising a sash frame having top and bottom end members and opposite side members and an outwardly opening channel extending along each of said opposite side members, a laterally shiftable tongue disposed in and extending along each channel, each of said tongues being adapted to be projected from the respective channel and retracted into said channel, a laterally shiftable pivot pin housed within each end of one of the end members of said sash frame, each of said pivot pins being adapted to be extended from and retracted into said end member, motion transfer means housed within each of the respective frame members and operatively connecting each tongue with its respective pivot pin for simultaneous shifting movement of the tongue by the pivot pin and in the opposite direction therefrom, and an operating means housed within said one end frame member and connected with each of the said pivot pins for actuating both said pivot pins in opposite directions relative to each other simultaneously.

8. A double hung sliding sash window construction comprising a window frame having opposed jambs each formed with transverse longitudinally extending steps providing a pair of transversely spaced shoulders facing in the same direction, the span between one opposing pair of steps of said jambs being less than the span between the other opposing pair of steps, a longitudinal groove in each step of each jamb, a window sash slidably mounted between each pair of opposing steps of the said jambs, a laterally shiftable tongue projecting from each side of each sash, each tongue being aligned with and extending into a respective jamb groove, a pivot bolt mounted on each side of each sash and adapted to be projected laterally therefrom, said pivot bolts being axially aligned with each other and said jambs having openings to receive said pivot bolts, and operating means on each sash adapted to extend the tongues and retract the pivot bolts thereof simultaneously, each sash being swingable

on its pivot bolts and away from the respective jamb shoulders when said pivot bolts are extended and said tongues are retracted.

9. A double hung sliding sash window construction comprising a window frame having opposed jambs each formed with transverse longitudinally extending steps providing a pair of transversely spaced shoulders facing in the same direction, the span between one opposing pair of steps of said jambs being less than the span between the other opposing pair of steps, a longitudinal groove in each step of each jamb, a window sash slidably mounted between each pair of opposing steps of the said jambs, a laterally shiftable tongue projecting from each side of each sash, each tongue being aligned with and extending into a respective jamb groove, a pivot bolt mounted on each side of each sash at one end thereof and adapted to be projected laterally therefrom, said pivot bolts being aligned with each other and said jambs having openings to receive said pivot bolts, motion transfer means connecting each tongue and its respective pivot bolt for mutual simultaneous shifting movement in opposing directions relative to each other, and operating means on each sash extending between said pivot bolts for simultaneously actuating the tongues and pivot bolts on both sides of the sash, each sash being swingable on its pivot bolts and away from the respective jamb shoulders when said pivot bolts are laterally projected.

DAVID T. BJORK.
